PURIFICATION OF BENZENE AND HOMOLOGUES THEREOF

Harold J. Hepp, Bartlesville, Okla., assignor to
Phillips Petroleum Company, a corporation of
Delaware

Application August 12, 1946, Serial No. 689,872

5 Claims. (Cl. 260—674)

1

This invention relates to the purification of benzene and its lower alkyl homologues. More specifically it relates to a process for the removal of olefins from benzene and its lower alkyl homologues.

Benzene and its lower alkyl homologues have long been products of commercial importance. The destructive distillation of coal has been and is a major source of such compounds. In more recent years, the cracking of petroleum has provided another source of these compounds, and the products of this operation at least much of the time contain benzene and alkyl benzene compounds in recoverable amounts.

Fractionation, with or without combination with such other methods as absorption, is used as a means of recovery and separation of these compounds from the cracked products. Such methods, however, do not readily yield pure products. Olefins, produced in large amounts by cracking of petroleum, are especially difficult to separate from aromatic compounds by such means, and, consequently, the aromatic compounds separated from mixtures of aromatics and olefins contain excessive amounts of olefins for many uses.

Treatment with sulfuric acid has been practiced in removing the olefins from these mixtures, although such side reactions as sulfonation leave much to be desired in this method.

Solid aluminum chloride has also been used as a treating agent in removal of olefin impurities from benzene and its lower alkyl homologues with satisfactory removal of olefins, but this method results in excessive loss of desired aromatics.

In copending application Serial No. 635,590 filed December 17, 1945, now issued as U. S. Patent 2,458,777, issued January 11, 1949, there is described a process whereby the olefinic content of an aromatic concentrate is removed by treatment with a fluid aluminum chloride-hydrocarbon complex. In this process, the olefin-containing aromatic concentrate is contacted with the fluid aluminum chloride complex, preferably in a countercurrent, multistage system, the olefins being polymerized and held by the aluminum chloride-hydrocarbon complex. Due to the high solubility of aromatics in the complex, the complex phase recovered from the process contains a high

2

proportion of the desired product of the process, and this complex phase is decomposed with water, and the oils contained in this phase are recovered and combined with the product hydrocarbons prior to fractionation for separation into desired products.

In the process of the copending application above-identified, however, the aluminum chloride is lost as a water solution and the very high boiling oils of the catalyst are included in the product stream going to the fractionating zone.

The principal object of the present invention is to provide an improved process for the removal of olefins from benzene and its lower alkyl homologues. Another object is to provide such a process wherein the aluminum chloride content of the aluminum chloride-hydrocarbon complex is maintained in a form such that it can be recovered. Another object is to provide a process of the foregoing type which is simple and economical. Numerous other objects will appear hereinafter.

According to the present invention, an olefin-containing aromatic concentrate is contacted with a fluid aluminum chloride-hydrocarbon complex, and the hydrocarbon phase is then separated from the complex phase. The hydrocarbon phase is substantially olefin-free and contains a small amount of dissolved complex. The complex phase contains a relatively large proportion of dissolved aromatics, and is extracted with a predominantly paraffinic and/or naphthenic hydrocarbon substantially free of olefins and of such boiling range that it is easily separated by fractionation from the extracted aromatic compound. The two hydrocarbon streams are then substantially freed of dissolved and suspended catalyst, and the contained product is recovered by suitable means, such as fractionation. The complex phase, substantially freed of dissolved aromatic content, may then be processed for recovery of anhydrous aluminum chloride.

The fluid aluminum chloride-hydrocarbon complex used in this process may be one especially made up for use in this process, or it may be excess complex discarded from an alkylation or isomerization process. Suitable complexes will have a heat of hydrolysis between about 200 and about 480 calories per gram, preferably between

280 and 380 calories per gram. Details of methods of making these complexes are well known in the art and need not be discussed here. A typical complex may be made by mixing aluminum chloride and kerosene (preferably substantially free from olefins and aromatics) in the weight ratio of 5 to 8 and has a heat of hydrolysis of 323 calories per gram.

The solubility of the aromatic compounds in a complex discarded from an ethylene-isobutane alkylation system has been found to be more than one volume of aromatic compound per volume of original complex. Thus, the complex phase separating from the effluent of the zone in which the olefin-containing aromatic concentrate and aluminum chloride-hydrocarbon complex are contacted will contain a high proportion of physically dissolved aromatics. The dissolved aromatics will usually amount to from about 40 volume per cent to about 65 volume per cent of the total complex phase. The complex will also contain some olefins held in the complex by chemical bonds. Extraction of the complex with a liquid paraffinic and/or naphthenic hydrocarbon yields an extract phase of paraffinic and/or naphthenic hydrocarbon and extracted aromatic, while the olefinic content of the complex is not extracted. The olefins are apparently present in the complex phase bound in some manner to the aluminum chloride and are thus not distributed between the hydrocarbon phase and complex phase when the extracting hydrocarbon is added.

The aromatic hydrocarbons will physically dissolve some aluminum chloride-hydrocarbon complex, though the solubility of complex in the aromatic hydrocarbon is much smaller than the solubility of aromatic hydrocarbon in the complex. At room temperature, the treated aromatic hydrocarbons usually hold in solution less than about two volume per cent complex. A portion of the dissolved complex may be separated from the aromatic hydrocarbon phase by addition of paraffinic and/or naphthenic hydrocarbons. It is preferable that the paraffinic and/or naphthenic hydrocarbons are of such boiling range that the added hydrocarbon is readily separated from the desired aromatic product by fractionation.

The proportions of the complex and the olefin-containing aromatic hydrocarbon may vary over wide limits. I often prefer to use such proportions that two phases, namely an aromatic hydrocarbon phase and a complex phase exist under the conditions of the contacting step. The amount of complex taken should be sufficiently large to effect complete or substantially complete removal of the olefin contained in the aromatic.

The proportions of the complex and the saturated hydrocarbon employed to extract the dissolved aromatic therefrom are preferably such that substantially all of the dissolved aromatic is extracted from the complex by the extractant hydrocarbon. In this way, loss of aromatic is kept at a minimum.

One specific embodiment of this invention in which olefin-containing benzene is treated is shown in the accompanying drawing, and the following description of the process with reference to the drawing will give a better understanding of this invention. Numerous valves, pumps and controls have not been included in this schematic drawing, but these can readily be supplied by those skilled in the art.

Olefin-containing benzene from a source not shown is introduced through pipe 10 to the lower

part of contactor 11. Through pipe 12 a fluid aluminum chloride-hydrocarbon complex with a heat of hydrolysis within previously-described limits is introduced in the upper section of contactor 11. The contactor 11 preferably is a packed tower or plate tower in which countercurrent flow of hydrocarbon and complex is maintained, intimate contacting of complex and hydrocarbons being facilitated by the packing or plates. The temperature in the contactor 11 may be from 40° F. to 250° F., preferably from 100° F. to 175° F., and the contactor is operated under sufficient pressure that substantially liquid phase is maintained. Though not here shown, contacting may be accomplished by mechanically agitated contactors, preferably in a multistage countercurrent system such as described in previously mentioned application Serial No. 635,590.

The treated benzene containing dissolved complex and some suspended complex is withdrawn from tower 11 through pipe 13, cooler 13a being utilized to cool the effluent if desired, and, through a T, pentane from a source to be described is added through pipe 24. The velocity through pipe 13 is such that turbulent flow is maintained and mixing of the pentane and benzene accomplished by this turbulence. The mixed pentane and benzene is conducted to settler 14, where the hydrocarbon and suspended complex separate to form an upper hydrocarbon phase containing a small amount of dissolved complex and a lower aluminum chloride-hydrocarbon complex phase containing dissolved hydrocarbon.

Substantially spent complex is removed from the bottom of the tower 11 through pipe 16, and complex accumulating in settler 14 is removed through pipe 15 and conducted to pipe 16. The combined stream then is conducted to stripper 17. If desired, a portion of this stream of complex and dissolved hydrocarbon may be recycled to the contactor 11 through pipe 28, pump 29, and pipe 30, and the remainder of the stream then conducted to stripper 17. The lower section of stripper 17, that below dotted line 18, functions as a countercurrent contacting section and may either be packed with a suitable packing material such as Raschig rings, Beryl saddles and numerous others, or may contain bubble cap trays or perforated trays. The upper section, that above dotted line 18, contains no packing or trays and functions as a settling zone. Pentane is introduced into stripper 17 at the bottom through pipe 25 from a source to be described, and the rising stream of pentane strips aromatics from the downflowing complex. The pentane and aromatics rise into the settling zone of stripper 17, where any suspended complex drops back to the stripping zone.

The complex, stripped of at least a major portion of its aromatic content, is removed from the bottom of stripper 17 through pipe 31 and is conducted to an aluminum chloride recovery system, not here shown. Any of the numerous processes for recovery of aluminum chloride from its hydrocarbon complex may be used, but I prefer to use the method described and claimed in copending application Serial No. 651,962 filed March 4, 1946.

The hydrocarbon from stripper 17 is removed through pipe 20 and the hydrocarbon phase from settler 14 is removed through pipe 19. The two are admixed and the combined stream thence conducted to caustic and/or water washer 21, where any dissolved aluminum chloride and/or dissolved and/or suspended aluminum chloride-

hydrocarbon complex is removed from the hydrocarbon. From washer 21, the hydrocarbon is conducted through pipe 22 to fractionator 23, where the pentane is taken overhead through pipe 24. A portion of the pentane is conducted through pipe 25 along a path previously described into the bottom of stripper 17, and the remainder is carried by pipe 24 through another previously described path into admixture with the benzene stream in line 13. Makeup pentane may be added to pipe 25 through pipe 26.

Benzene and heavier are removed from fractionator 23 through pipe 27, thence to product fractionation, not shown, if purification is desired; or this stream may be conducted to storage if of sufficient purity for the use to which it is put.

It is preferred that the paraffinic and/or naphthenic hydrocarbon used to extract aromatics from the complex be lower boiling than the aromatic compound undergoing purification. In some specific embodiments of this invention, however, it is possible to utilize a higher boiling extracting hydrocarbon. In either event the boiling point of the extracting hydrocarbon should be sufficiently far removed from that of the aromatic hydrocarbon to be readily separated therefrom by ordinary fractional distillation.

Examples of saturated hydrocarbons which may be employed for the extraction of the dissolved aromatic hydrocarbon from the liquid aluminum chloride-hydrocarbon complex are acyclic paraffins such as liquid propane, liquid butane (either normal or iso), normal pentane, isopentane, any of the hexanes, any of the heptanes, any of the octanes, cyclic paraffins such as cyclopentane, cyclohexane, methyl cyclopentane, methylcyclohexane, mixtures of any two or more of the foregoing such as occur in the form of straight-run naphtha, kerosene, natural gasoline, etc., provided only that the boiling point be sufficiently removed from benzene or other recovered aromatic to afford easy separation from the recovered aromatic.

The extractant should be relatively free from olefins or other objectionable impurities such as diolefins, acetylenes, sulfur, sulfur compounds, etc. In most cases it is undesirable to use an extractant which forms an azeotrope with the aromatic. Thus normal hexane, methylcyclopentane and cyclohexane are reported to form azeotropes of the minimum-boiling type with benzene and normally would not be employed as extractant hydrocarbons for benzene.

Pentane such as normal pentane or isopentane or a mixture of normal pentane and isopentane is often preferred for carrying out the extraction step because pentane boils sufficiently low that it can be easily separated from the benzene or other aromatic and at the same time it is maintained in the liquid state without the use of excessive pressures such as would be required if propane or either of the butanes were employed.

The aromatic hydrocarbon purified in accordance with the present invention is usually benzene; however instead of benzene other lower alkyl homologues thereof may be purified. Examples are toluene, ethylbenzene, cumene and xylene. The invention is primarily applicable to monocyclic aromatic hydrocarbons selected from the group consisting of benzene and its lower alkyl homologues, that is compounds derivable from benzene by replacement of one or more nuclear hydrogen atoms with lower alkyl

groups, i. e. those having from one to four carbon atoms including methyl, ethyl, n-propyl, isopropyl, n-butyl, secbutyl, isobutyl, tert-butyl.

Example

Twenty-five cc. of an aluminum chloride-hydrocarbon complex discarded from an ethylene-isobutane alkylation system was saturated with benzene, the final volume being 55.5 cc. The benzene-saturated complex was extracted with isopentane; 66.5 cc. of hydrocarbon phase and 37 cc. of complex phase were recovered. By refractive index analysis, the hydrocarbon phase was found to contain 34 volume per cent benzene.

The extracted complex phase was again extracted with a second 50 cc. portion of isopentane, and 31 cc. of complex phase and 55.5 cc. of hydrocarbon phase were recovered. By refractive index analysis, the hydrocarbon phase was found to contain 12 volume per cent benzene.

The extracted benzene was calculated to be 29.2 cc., or a recovery of over 95 per cent of the benzene dissolved in the complex.

I claim:

1. A process for removing olefins from monocyclic aromatic hydrocarbons which comprises liquid-liquid extracting an olefin-containing monocyclic aromatic hydrocarbon with liquid aluminum chloride-hydrocarbon complex having a heat of hydrolysis of from 200 to 480 calories per gram to effect the removal of the olefin from the aromatic hydrocarbon by said complex in the form of an olefin-containing aluminum chloride-hydrocarbon complex, a portion of said aromatic hydrocarbon dissolving in said aluminum chloride-hydrocarbon complex, withdrawing from the extracting step the resulting olefin-free aromatic hydrocarbon phase and the resulting complex phase, introducing saturated hydrocarbon selected from the group consisting of paraffins and naphthenes to said aromatic hydrocarbon phase and thereby precipitating entrained complex therefrom, liquid-liquid extracting said complex phase with saturated hydrocarbon easily separable from the aromatic hydrocarbon and selected from the group consisting of paraffins and naphthenes, withdrawing an extract phase of saturated hydrocarbon and aromatic hydrocarbon and a raffinate phase of extracted aluminum chloride complex, caustic washing all of said separated aromatic hydrocarbon to remove any aluminum chloride or aluminum chloride - hydrocarbon complex, separating the resulting extract and recovering aromatic hydrocarbon as a product of the process.

2. A process for removing olefins from monocyclic aromatic hydrocarbons, which comprises liquid-liquid extracting the olefin-containing monocyclic aromatic hydrocarbon with sufficient quantity of a liquid aluminum chloride-hydrocarbon complex having a heat of hydrolysis of from 200 to 480 calories per gram to remove all of the olefins from said aromatic hydrocarbon, simultaneously dissolving a portion of said aromatic hydrocarbon, recovering an aromatic fraction free of olefins and containing only small quantities of said complex dissolved and in suspension, separating a portion of said complex from said aromatic hydrocarbon by admixing with said fraction a low-boiling paraffin hydrocarbon and allowing said complex to settle out from said admixture as a separate phase, liquid-liquid extracting the olefin-aromatic-aluminum chloride

complex with a low-boiling paraffin hydrocarbon to remove said portion of aromatic hydrocarbon from said complex phase, combining the aforesaid aromatic fraction and the portion of aromatic removed from said complex phase, caustic washing said combined aromatics removing all dissolved aluminum chloride complex, and recovering purified olefin-free monocyclic aromatic hydrocarbons as a product of the process.

3. A process according to claim 2 wherein said combined aromatics are caustic washed while in admixture with said low-boiling paraffin hydrocarbon, fractionating said caustic washed material to recover said low-boiling paraffin from said aromatics for recycle, and passing a part of said low-boiling paraffin to admixture with said aromatic fraction and another part to admixture with said complex phase as described.

4. A process for removing olefins from monocyclic aromatic hydrocarbons which comprises liquid-liquid extracting an olefin-containing monocyclic aromatic hydrocarbon at a temperature in the range of 40 to 250° F. with a sufficient quantity of a liquid aluminum chloride-hydrocarbon complex having a heat of hydrolysis of from 200 to 480 calories per gram to effect the removal of all of the olefin from the aromatic hydrocarbon by said complex, simultaneously dissolving a portion of aromatic in said complex, with drawing from the extracting step the resulting olefin-free aromatic hydrocarbon phase and the resulting complex phase, introducing saturated hydrocarbon selected from the group consisting of low-boiling paraffins and naphthenes to said aromatic hydrocarbon phase and thereby precipitating entrained complex therefrom, liquid-liquid extracting said complex phase with saturated hydrocarbon selected from the group consisting of low-boiling paraffins and naphthenes and separable from the aromatic hydrocarbon by ordinary fractional distillation and thereby effecting selective extraction of the aromatic hydrocarbon dissolved in said complex without extracting any olefin from said complex, withdrawing a thus separated extract phase of low-boiling saturated hydrocarbon and aromatic hydrocarbon and a raffinate phase of extracted complex, caustic washing all of said separated aromatic hydrocarbon to remove any aluminum chloride or aluminum chloride-hydrocarbon complex dissolved or suspended therein, and fractionally distilling the resulting extract to separate a fraction of said saturated hydrocarbon suitable for recycle to said second extracting step and to said precipitating step and a fraction of olefin-free aromatic hydrocarbon.

5. The process of removing olefins from benzene which comprises liquid-liquid extracting the olefin-containing benzene with an aluminum

chloride-hydrocarbon complex having a heat of hydrolysis of from 280 to 380 calories per gram, said complex being present in sufficient quantity to remove all of said olefins, the proportions of said benzene and said complex being such that two phases exist under the conditions of the extracting step, conducting said extracting step at a temperature of from 100 to 175° F. and a pressure such as to maintain liquid phase conditions, thereby effecting removal of the olefins from the benzene by the complex and simultaneous dissolution of benzene in said complex in an amount corresponding to from 40 to 65 volume per cent of the resulting complex, with drawing from the extracting step a substantially olefin-free benzene phase containing a small amount of dissolved complex, also withdrawing from said extracting step the resulting complex phase, intimately contacting said benzene phase containing dissolved complex with liquid pentane and thereby causing the dissolved complex to precipitate, separating the thus precipitated complex and combining same with the complex resulting from said extracting step, countercurrently extracting in a second extracting step the resulting complex in liquid-liquid manner with liquid pentane and thereby effecting selective extraction of substantially all of the benzene dissolved in said complex without extracting any olefin from said complex, withdrawing from the second extracting step an extract phase consisting essentially of the pentane and the benzene and a raffinate phase consisting of extracted complex, washing said extract phase with an aqueous solution capable of removing any aluminum chloride or aluminum chloride-hydrocarbon complex contained therein, passing the resulting extract to a fractional distillation zone and there fractionally distilling same to separate same into an overhead fraction of pentane and a bottoms fraction of olefin-free benzene, and recycling said overhead fraction of pentane both to said step of admixing pentane with said benzene phase and to said step of extracting said complex phase with pentane.
